The ornamental design for a handgrip for a child's snow shovel, as shown.

DESCRIPTION

FIG. 1 is a perspective view of a handgrip for a child's snow shovel showing our new design;

FIG. 2 is a front view thereof;

FIG. 3 is a left side view thereof, the right side view being a mirror image and symmetrical thereto;
FIG. 4 is a back view thereof;
FIG. 5 is a top view thereof;
FIG. 6 is a bottom view thereof;
FIG. 7 is an enlarged perspective view of the handgrip for a child's snow shovel showing or new design;
FIG. 8 is a front view thereof;
FIG. 9 is a right side view thereof, the left side view being a mirror image and symmetrical thereto;

FIG. 10 is a back view thereof;
FIG. 11 is a top view thereof; and,
FIG. 12 is a bottom view thereof.

The broken line portions of the drawing disclosure are for illustrative purposes only and form no part of the claimed design.
